UNITED STATES PATENT OFFICE.

JACOB ZITZERMAN, OF BROOKLYN, NEW YORK.

COMBINED SOUNDING BOX AND SPEAKING UNIT.

Application filed October 6, 1925. Serial No. 60,842.

This invention relates to sound-conveying and sound-reproducing devices and comprehends a combined sound box and speaking unit, by means of which sounds may be reproduced from a record of a talking machine or conveyed by radio.

One of the outstanding objects of the present invention resides in the provision of a member including a diaphragm and separate means for mechanically and electrically vibrating the diaphragm to reproduce or transmit sounds, thereby eliminating in accordance with the common practice, the necessity of removing and replacing a talking machine sound box with a radio speaking unit when it is desired to employ the amplifying chamber of the talking machine as a loud speaker for a radio.

The invention furthermore comprehends in a combined sound box and speaking unit including the diaphragm and separate means for mechanically and electrically actuating the same, means for adjusting the electrical actuating means whereby to dispose the same in a retractive position out of the vibratory path of movement of the diaphragm when the same is mechanically actuated so as to prevent interference with the mechanical reproduction of sounds.

The invention furthermore comprehends a combination sound box and speaking unit equipped with detachable means for connecting the sound box with a radio receiving set when the diaphragm of the sound box is to be mechanically vibrated by the needle and record.

The invention still further comprehends a combined sound box and speaking unit of the character set forth which is comparatively simple in its construction and mode of use, which is inexpensive to produce, and which is highly efficient in its purpose.

With the above recited and other objects in view reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

Figure 1 is a perspective view illustrating the combined sound box and speaking unit

in its applied relation to a talking machine;

Fig. 2 is a side view of the same;

Fig. 3 is a sectional view therethrough taken approximately on the line 3-3 of Fig. 2;

Fig. 4 is a sectional view taken approximately on the line 4-4 of Fig. 3.

Referring to the drawings by characters of reference, the combined sound box and speaking unit includes a housing or casing 10, which is closed except for the sound outlet boss 11 which is designed to fit upon and establish communication with the usual tone arm A of a talking machine B, which tone arm leads to and communicates with the sound amplifying chamber C. Arranged within the housing 10 is a magnetically susceptible diaphragm 12, to which is connected in the usual manner, a needle bar 13 with which the usual needles are associated, which needles have co-operation with the grooves of the record E of a talking machine for mechanically vibrating the diaphragm to reproduce sounds. Arranged within the housing or casing 10 is an electromagnet 14 carried by a base 15 mounted for movement on guide pins 16 which extend through openings 17 in the base. The base 15 is adjustable to advance the core 18 of the magnet toward or retract the same from the diaphragm 12 through the medium of an adjusting device 19 specifically illustrated by way of example, as a threaded shank swiveled at 20 to the base and extending through a complementary threaded bearing 21 in the side wall of the housing 10. The shank is provided at its outer end with a manipulating knob or head 22 disposed exteriorly of the casing for effecting the adjustment of the base and magnet. The base and outer side wall of the housing 10 are provided with alined apertures 23 and 24, and the base carries spaced contact elements 25 which extend beyond the aperture 23 for engagement with a jack 26 connected to a radio receiving set by means of a conductor 27 whereby the magnet is electrically connected with the set.

In use and operation, when the device is employed in its capacity as a sound box for a talking machine, the knob 22 is manipulated to retract the base 15, whereby to dispose the core 18 of the magnet 14 in a position sufficiently spaced from the diaphragm to prevent any interference with the vibra-

tion thereof by the needle D. When used in this capacity the jack is removed to disconnect the magnet from the radio set so that the conductor will not interfere with the closing of the cover of the talking machine.

When used in the capacity of a speaking unit, the knob 22 is manipulated to advance the magnet core 18 to a position in close proximity to the diaphragm for causing the vibration thereof. When employed as a speaking unit, it is desired to exclude the air from the interior of the casing as much as possible, while when the device is used in the capacity of a sound box it is essential to permit of free circulation of air therethrough, and for this reason the casing is apertured at 28 and provided with a closure plate 29 having apertures 30, the plate being slidable for the purpose of disposing the apertures 28 and 30 in and out of register.

What is claimed is:—

1. As a new article of manufacture, a combined sound box and speaking unit, including a diaphragm, separate means for mechanically and electrically actuating the diaphragm, a housing therefor, and means for venting the housing when using the same in the capacity of a sound box and for closing the housing when using the same in the capacity of a speaking unit.

2. As a new article of manufacture, a combined sound box and speaking unit, including a diaphragm, separate means for mechanically and magnetically actuating the diaphragm a housing therefor having venting apertures, and a shiftable closure for said venting apertures, whereby the

housing may be vented when used as a sound box and closed when the same is employed in the capacity of a speaking unit.

3. A combined sound box and speaking unit, comprising a housing, a magnetically susceptive diaphragm in said housing, a needle bar connected with the diaphragm for mechanically vibrating the same, and electromagnetic means for magnetically actuating the same said housing having venting apertures open to the atmosphere when the same is mechanically operated, and a closure for said venting apertures for closing the housing when the same is magnetically operated.

4. A combined sound box and speaking unit, comprising a housing, a magnetically susceptive diaphragm in said housing, a needle bar connected with the diaphragm for mechanically vibrating the same, and electromagnetic means for magnetically actuating the same, said electromagnetic means being adjustable toward the diaphragm when the same is magnetically operated and adjustable away from the diaphragm when the same is mechanically operated.

5. As a new article of manufacture, a combined sound box and speaking unit, including a diaphragm and separate means for mechanically and electrically actuating the diaphragm, the means for electrically actuating the diaphragm being adjustable whereby to dispose the same in a position out of the vibratory path of movement of the diaphragm when mechanically actuated.

JACOB ZITZERMAN.
